UNITED STATES PATENT OFFICE.

HUGH C. TYLER, OF COLUMBUS, OHIO.

VACUUM-CLEANER.

1,218,134.

Specification of Letters Patent.

Patented Mar. 6, 1917.

Application filed October 28, 1915. Serial No. 58,314.

To all whom it may concern:

Be it known that I, HUGH C. TYLER, a citizen of the United States, residing at Columbus, in the county of Franklin and State of Ohio, have invented certain new and useful Improvements in Vacuum-Cleaners, of which the following is a specification.

This invention relates to vacuum cleaners of the type using a brush structure, or its equivalent, for disturbing the nap of a rug or the like as the cleaner is moved back and forth over the same. As is well known, suction cleaners as now on the market employ an electric motor, it being essential that this motor be operated at a very high rotative speed, in order to produce the correct amount of suction. On the other hand, it is desirable that the brush should not be rotated at an excessive speed, since to do so destroys the nap instead of merely disturbing it to permit the more ready removal of dirt, lint and ravelings.

My invention, therefore, resides in a structure of connection between the operating motor and the brush structure, this connection being of such nature that the rotative speed of the brush may be considerably reduced and at the same time will not alter the appearance of the machine as a whole.

The preferred embodiment of my invention is shown in the accompanying sheet of drawings, in which similar characters of reference designate corresponding parts, and in which:

Figure 1 is a central vertical section through the suction end of a vacuum sweeper to which my invention has been applied,

Fig. 2 is a section taken on line 2—2 of Fig. 1 and looking in the direction of the arrows, and,

Fig. 3 is a central longitudinal section through the brush and its supporting structure.

In these drawings, there is shown a motor casing 1 within which the ordinary electric motor is carried and which motor has its armature shaft extended as is shown at 2 to project into the fan casing 3, as shown. In this fan casing and on the extension 2 there is mounted the usual type of fan 4, the arrangement being such that rotation of the fan will cause a suction of air through the centrally disposed opening 5 from the suction nozzle designated generally by the reference numeral 6, this suction nozzle communicating with the fan chamber 3 by means

of the communicating passage shown at 7. It will be noted that the nozzle 6 is provided with bearings 8 at each end, these bearings serving to rotatably support a rotatable brush formed in two sections 9 and 10. The center portion of the suction nozzle 6 is also provided with a housing member such as is shown at 11, this housing member having its opposite walls provided with transversely arranged and alining holes into which the oil soaked bearing members 12 are designed to fit. These alining holes are also provided with enlarged concentric sockets 13 into which the ferrules 14 carried by the adjacent ends of the brush sections are designed to fit. These ferrules are each preferably made of frusto-conical form to prevent ravelings, etc., from winding themselves into the bearing portions and each is further provided with a square socket to receive the square stud 15 formed on each end of a shaft 16, this shaft also rigidly carrying within the hollow portion of the housing a worm wheel 17. The housing member 11 also rotatably supports a worm shaft 18 arranged to stand in a substantially vertical direction and being further formed with a worm 19 designed to coöperate with the worm wheel 17. By this means, a very great reduction in the rotative speed between the shaft 18 and the worm wheel 17 may be attained and this accomplished without necessarily increasing the size of the parts of the cleaner or in giving it an unsightly appearance. The upper end of the shaft 18 is extended a slight distance to receive a pulley or sheave such as is shown at 20 and this pulley 20 is designed to coöperate with a similar pulley 21 carried by the lower end of the armature shaft extension 2. These pulleys may or not be of the same size according to the speed reduction between the gears 16 and 19, but both pulleys are preferably of a grooved nature and receive an elastic belt such as is shown at 22, this belt serving as the driving connection between the armature shaft and the shaft 18. The belt 22 is also preferably made of a highly elastic material so that it will always maintain a good frictional grip on the pulleys without the use of a dressing.

From the foregoing description, it will be apparent that I have provided a type of structure wherein the desired reduction in rotative speed of the fan shaft and the brush shaft may be attained in a comparatively

simple manner. Rotation of the fan shaft 2 causes rotation of the shaft 18 by means of the pulleys 20 and 21 and the belt 22. The speed between these shafts may be reduced 5 slightly if desired by varying the sizes of these pulleys and this rotative movement is then imparted to the brushes by means of the connection between the worm wheel 17, and the worm 19. It will also be noted that 10 each of the brush sections 9 and 19 may be removed without removing the housing structure 11, since the ends of the nozzle are provided with a bearing member 8 held in position by its threaded engagement as is 15 shown. Each of these brushings is provided with a centrally disposed socket into which the stud 24 on the caps or ferrules on the outside ends of the brushes rotatably fit. These brush sections may then be removed 20 by unscrewing their respective bearings 8 and pulling the entire brush through the hole thus formed, the detachable connection formed by the square stud 15 and the square socket in the ferrules 14 permitting this 25 movement.

What I claim, is:

1. In a vacuum sweeper, the combination with a motor, a suction chamber, and a nozzle communicating therewith, of a brush in 30 said nozzle, a housing member in said nozzle, a shaft carried by said housing in driving relation with said brush, a worm wheel within said housing rigidly carried by said shaft, a worm shaft journaled in said housing, a worm on said worm shaft meshing 35 with said worm wheel, a pulley on said worm shaft, an extension on the motor armature shaft, a pulley on the lower end of said extension, and a belt between said two 40 pulleys.

2. In a vacuum cleaner, the combination with a motor and suction chamber and a nozzle communicating therewith, of a pair 45 of brush sections the adjacent brush ends being formed with polygonal sockets, a hous-

ing member in said nozzle, a stub shaft rotatably journaled in said member, said shaft having polygonal shaped ends to fit said sockets, and means for rotatably driving 50 said shaft.

3. In a vacuum cleaner, the combination with a motor, a suction chamber, and a nozzle communicating therewith, of a brush rotatably journaled in said nozzle, said nozzle having an opening in one end wall large 55 enough to accommodate the passage of such brush therethrough, and a removable bearing member in which the end of said brush is journaled removably secured in said opening.

4. In a vacuum cleaner, the combination with a motor, a suction chamber and a nozzle communicating therewith, of a housing member rigidly secured in said nozzle, driving gearing in said housing, a brush section 65 located on each side of said member, and a detachable driving connection between each of said sections and said gearing.

5. In a vacuum cleaner, the combination with a motor, a suction chamber and a nozzle communicating therewith, of a pair of brush sections in said nozzle, a bearing support in said nozzle between the brush ends, a driving shaft journaled in said support, detachable driving connections between said 75 shaft and the brush ends engaging the same, means for rotating said shaft, the ends of said nozzle being provided with openings large enough to accommodate the passage of the respective brush sections therethrough, 80 and removable bearing members secured in said openings into which the ends of said brushes are supported.

In testimony whereof I affix my signature in presence of two witnesses.

HUGH C. TYLER.
